(57) **CLAIM**

The ornamental design for a cellphone holder with optical instrument adapter substantially, as shown and described.

DESCRIPTION

FIG. 1 is a rear perspective view of a bracket for cellphone holder with optical instrument adapter.

FIG. 2 is a front perspective view of the bracket for cellphone holder with optical instrument adapter.

FIG. 3 is a rear elevational view of the bracket for cellphone holder with optical instrument adapter.

FIG. 4 is a front elevational view of the bracket for cellphone holder with optical instrument adapter.

FIG. 5 is a right-side elevational view of the bracket for cellphone holder with optical instrument adapter.

FIG. 6 is a left-side elevational view of the bracket for cellphone holder with optical instrument adapter.

FIG. 7 is a top plan view of the bracket for cellphone holder with optical instrument adapter; and,

FIG. 8 is a bottom plan view of the bracket for cellphone holder with optical instrument adapter.

The broken lines depict portions of the article that form no part of the claimed design.

1 Claim, 8 Drawing Sheets
